H. C. PARSONS, OF DEXTER, MAINE.

Letters Patent No. 95,259, dated September 28, 1869.

IMPROVED MOP-HEAD.

The Schedule referred to in these Letters Patent and making part of the same.

To all whom it may concern:

Be it known that I, H. C. PARSONS, of Dexter, in the county of Penobscot, and State of Maine, have invented a new and useful Improvement in Mop-Heads; and I do hereby declare that the following is a full, clear, and exact description thereof, which will enable those skilled in the art to make and use the same, reference being had to the accompanying drawings, forming part of this specification.

This invention relates to an improvement in the method of holding the yarn or rags in mops, or in the construction of the mop-head; and

It consists in providing the jaws of the head with teeth for holding the rags, and in the method of forcing and holding the jaws together on the rags, as I will proceed to describe.

The drawing represents a longitudinal view of the head with the mop-handle attached.

A is the handle.

B is the part of the head to which the handle is attached, as seen in dotted lines at C.

D is the movable part of the head, which slides on the handle, and which is guided by the grooved end of the part B, (or the upper jaw,) as seen at e e, in the drawing.

F is the lower jaw.

The red coloring represents the rags, which form the mop or swab.

The lower jaw F is convex, or rounded on its upper side, and provided with teeth, as seen in the drawing.

The upper jaw B is concave, and also provided with teeth, which are seen in dotted lines in the drawing.

These teeth penetrate the rags, or other material forming the mop, and serve to prevent their slipping from the jaws.

For the purpose of forcing the two jaws toward each other, and thereby squeezing the rags between them, I place a double tubular cam, G, between the tubular parts of the head, or the parts marked h and i.

This double cam revolves on the handle, and the parts h and i are made so as to correspond where they come in contact with it.

It will be seen, that by turning the cam to the right, the jaw F will be forced upward and the jaw B will be forced downward, and the rags will be squeezed between them as much as may be desired.

When the double cam G has been turned once round, or nearly so, the teeth in the jaws will nearly or quite come in contact with each other.

The middle portion of the cam G is formed with concave circles, or in any other shape to allow of a good hold for the hand in turning it.

For the purpose of holding it in any desired position, one of its edges (where it comes in contact with i) is serrated, or formed with depressions and projections, as seen at J, and on the edge of the part i, as seen at o, there is a single projection, which fits into the depressions in J, and the elasticity of the rags keeps these parts engaged with each other, and prevents the cam from turning back when the mop is in use.

I am aware that a single rotary tubular cam has been applied to the handle, and to operate the movable jaw of a mop-head, the same being as represented in the patent of Randlett, dated November 15, 1858; therefore I make no claim thereto.

I employ a duplex tubular cam, as explained, provided with a rack or series of notches on one inclined edge, to operate with a tooth and oblique helical edge of the stationary jaw, and also with a corresponding obliquity applied to or extending from the yoke of the movable jaw. The duplex cam, formed and arranged with the two oblique surfaces against which it operates, has important advantages over the single cam, as it allows the jaws to open double the distance, so as to take in a thicker mop, and it enables the rack to be employed, which could not be well used to advantage with a single cam, formed to produce, by the same degree of rotary movement of it, the same degree of movement of the jaw; for, with the single cam the obliquity, under such circumstances, would be too great for the rack to be used to good advantage.

I therefore claim as my improvement—

The combination of the toothed jaws B F, tubular parts h i, and double cam G, all constructed and arranged to operate as herein described, for the purpose specified.

H. C. PARSONS.
